VAULT AIR CONDITIONING CONSTRUCTION
Nancy L. Strickland, North Canton, and Robert L. Schutt,
Canton, Ohio, assignors to Diebold, Incorporated,
Canton, Ohio, a corporation of Ohio
Filed Aug. 12, 1963, Ser. No. 301,390
4 Claims. (Cl. 98—39)

This invention relates to a ventilator for a bank vault and more particularly it pertains to a valve for opening and closing an air ventilating conduit leading to a vault.

Ventilating devices for bank vaults and the like have been used primarily as emergency means where a person is locked in a vault either intentionally or accidentally. A device for such an emergency is generally referred to as a "vault ventilator." Such a ventilator is usually provided with two air ports, one to remove stale air and the other to provide fresh air by means of a built-in automatic fan.

Moreover, such devices have provided not only for voice communication to the outside but have permitted direct access for transferring of food and liquids. The vault air conditioning construction of this invention is not an emergency device. Rather it provides for regular ventilation and air conditioning of a vault during the time when the vault door is open.

The atmosphere within a vault must be ventilated and conditioned because window openings through which air normally enters a room are not provided for most vaults. An expedient way to ventilate a vault is to penetrate a vault wall and introduce conditioned air from the same source of air conditioning provided for the building in which the vault is located.

Manifestly, each opening in a vault wall introduces a problem of maintaining vault security. Prior devices for ventilating bank vaults have not completely solved all of the security problems arising where built-in openings are formed in a vault wall.

Associated with the foregoing is a problem of controlling the vault air conditioning arrangement. Ordinarily, an air ventilator for a room is controlled by means solely within the room. For maximum security, however, additional controls should be provided outside of the vault to stop operation of the ventilator or access to the vault through the ventilator opening when the vault is closed, such as when personnel forget to close the access opening before closing the vault.

When the ventilator means is not closed before the vault door is closed, a ventilator valve is open which reduces the degree of security which should be maintained. Exterior control means should be provided for closing the air conduit through the vault wall. On the other hand, the means for opening the ventilator means must be maintained within the vault in the event a person is inadvertently locked into prevent suffocation.

An air ventilating device should also be provided with interior and exterior indicator lights which denote the specific condition of the device, i.e., whether on or off. If the ventilator is off, an exterior indicator light should be on. When the exterior light is off, however, it indicates that the ventilator is either unlocked, or the power has failed.

Such a combination of controls and lights provides for greater security in air conditioning a vault.

It has been found that a vault air conditioning arrangement may be provided in conjunction with the central air conditioning and ventilating system of the building in which the vault is located. Although the equipment penetrates the wall of the vault, it does not substantially reduce the security of the vault. The improved device uses a rotary valve mounted in and op-

2

erated at the inner surface of the vault wall. Controls for turning the valve on and off are likewise provided within the vault, but an additional control for turning it off may be provided outside of the vault in order to permit closing of the valve when it is inadvertently left on before closing the vault door. Suitable indicator lights may be provided in conjunction with the control means.

Accordingly, it is a general object of this invention to provide a vault air conditioning construction which is primarily an air conditioning and ventilating means for the vault atmosphere when the vault door is open.

It is another object of this invention to provide a vault air conditioning construction which is secondarily used for ventilating the vault when a person is inadvertently locked in.

It is another object of this invention to provide a vault air conditioning construction which penetrates the vault wall and communicates with the central air conditioning system of the building in which the vault is located without substantially minimizing security.

It is another object of this invention to provide a vault air conditioning construction which provides control means and indicating lights within the vault.

It is another object of this invention to provide a vault air conditioning construction which provides an indicator light for the locked position of the valve and which also provides a control for closing the valve when the indicator light is off.

It is another object of this invention to provide a vault air conditioning construction which is used in conjunction with a regular air system of the building in which the vault is located and which construction is devoid of an air fan.

Finally, it is an object of this invention to provide an improved air conditioning construction which is easily operated and which requires a minimum of maintenance and repair.

These and other objects are accomplished by the parts, constructions, arrangements, combinations and subcombinations comprising the present invention, a preferred embodiment of which—illustrative of the best mode in which applicants have contemplated applying the principles—is set forth in the following description and illustrated in the accompanying drawings, and which is particularly and distinctly pointed out and set forth in the appended claims forming a part hereof.

The present invention may be described in general terms as comprising a bank vault having a wall with a ventilator opening therethrough, the ventilator opening communicating with an air conduit of a central ventilating system, a rotary valve extending across the ventilator opening and rotatably mounted on trunnions at the inner surface of the vault wall, the valve having an air passage alignable with the air conduit when the valve is in an open position, the valve having an air blocking surface alignable with the air conduit when the valve is in the closed position, a motor connected to one of the trunnions, means for limiting the degree of rotation of the motor to 90° arcs for each operation of the motor, said means including an actuator disc on the shaft, a pair of radially opposed switch pins on at least one side of the disc, a first limit switch mounted in the path of rotation of the switch pins, a second limit switch mounted in the path of rotation of the switch pins and spaced 90° from the first switch, solenoid means in conjunction with the motor for locking the rotary valve in the open and closed positions, the solenoid means including a lock pin and pin-receiving recess in the valve, the lock pin being spring-biased in the recess in each of the open and closed positions, the lock pin being movable out of the pin-receiving recess upon actuation of the solenoid, and control means for rotating the valve to the

open and closed positions including a switch for actuating the rotary valve to the open and closed positions within the vault and including a switch exterior of the vault wall for actuating the rotary valve to the closed position.

In the drawings which are illustrative of the preferred embodiment of the invention, by way of example, and in which similar numerals refer to similar parts:

FIGURE 1 is a vertical sectional view through a bank vault;

FIG. 2 is an elevational view of the improved power operated security valve construction with parts broken away and in section;

FIG. 3 is a horizontal sectional view taken on the line 3—3 of FIG. 2;

FIG. 4 is a vertical sectional view taken on the line 4—4 of FIG. 2;

FIG. 5 is a vertical sectional view taken on the line 5—5 of FIG. 3; and

FIG. 6 is an electrical diagram.

In FIG. 1 a vault is generally indicated at 1. It includes a rear wall 2, a front wall 3, and a top wall 4. The front wall is provided with an entry opening 5 for a vault door (not shown). A conduit 6 extends from the rear wall 2 and is part of a central ventilator and air conditioning system (not shown) for the building in which the vault 1 is situated.

A ventilator opening 7 extends through the rear wall 2 and communicates with the conduit 6 at a level below the top wall 4 and below a false ceiling 8 which may be provided under the top wall. The opening 7 is shown in the rear wall 2. It is understood, however, that it may be situated in any other wall of the vault 1 such as the top wall 4 with the conduit 6 extending thereto.

As shown in FIG. 4 the opening 7 in the wall 2 includes a portion 7a and an enlarged portion 7b. The portion 7a is preferably lined with a sheet metal liner 9 which communicates with and is connected to the conduit 6. The opening portion 7a extends inwardly from the exterior vault surface to a location substantially midway between exterior and interior vault wall surfaces and it communicates with the enlarged opening portion 7b.

The enlarged opening portion 7b is encased within a housing which includes upper and lower housing plates 10 and 11, back plate 12, and opposite end plates 13 and 14 (FIG. 3). The plates 10 and 14 are substantially heavier than the liner 9. The plate 12 which is vertically disposed across opening portions 7a and 7b is of particularly heavy gauge metal. The plates 10 and 11 are welded at 15 to the plate 12, as shown.

The ventilator includes a rotary valve body 17 which is preferably circular in cross section and is enclosed within a pair of arcuate plates 18 and 19 which form cylindrical wall portions. The valve body 17 also includes a pair of spaced flat plates 20 and 21 which together with the arcuate plates 18 and 19 define a passage or radial slot 22 through the valve body 17. The plates 18—21 are mounted at opposite ends on end members 23 and 24 in which drive trunnion 25 and stub trunnion 26, respectively, are mounted at opposite ends. The trunnions are mounted in pillow blocks or journals 27 and 28, which in turn are mounted on spacer blocks 29 and 30, respectively, on the back plate 12. Thus, the valve body 17 is centrally disposed and rotatably mounted within the housing passage or opening 7b. The closed position of the valve body 17 is shown by the broken line positions of the flat plates 20 and 21 (FIG. 4).

When the valve 17 is turned through 90° arc increments, it turns the radial slot 22 between the closed and open positions. In the closed position one of the arcuate plates 18 and 19 is disposed across an opening 31 in the back plate 12 which opening is aligned with the opening portion 7a. In the open position the passage 22 is aligned with the opening 31 so that forced air from the conduit 6 and opening 7 passes through the valve 17 and into the interior of the vault 1.

To minimize air leakage into the area between the valve and the plates 10, 11, and 12, air baffles 32 are provided between the valve and the rear plate 12. An access cover 34 having an opening aligned with opening 31 is mounted on the inner vault wall side of the ventilator by spaced screws 35. Air baffles 33 also are provided between the cover 34 and valve and for security the cover 34 is held in place by spaced bars 34a and retainer bolts 34b.

For greater security the arcuate plates 18 and 19 and the air baffle 32 and 33 are preferably composed of copper secured to the plates 20 and 21 and members 23 and 24 by screws 19a. Copper cannot be burned away by a blow torch if an attempt is made from the outside of the wall through the opening portion 7a. By providing the plates 18 and 19 in the baffle 32 as copper members, it is virtually impossible to break into the vault 1 through the opening 7.

Means for rotating the valve in one direction are generally indicated at 36 and include a motor 37 and reduction gear means 37a. The motor is mounted on a spacer block 38 on the rear wall 12. In addition, drive control means are also provided for stopping rotation of the valve body 17 after each 90° arc increment of rotation, which means include an actuator disc 39, spacer limit switches 40 and 41, and switch actuator pins 42 and 43. Two pins 42 are mounted at 180° one side of the disc 39 and two pins 43 are similarly mounted on the other side of the disc. The switches 40 and 41 are in the normally closed position so that the motor 37 operates to turn the valve 17. When the pins 42 and 43 actuates one or the other of the switches 40 and 41, the motor 37 stops. The switches 40 and 41 are spaced 90° from each other so that operation of the motor 37 is always limited for each actuation to movement of valve body 17 through a 90° arc increment.

In addition to the foregoing, means are provided for locking the valve in each open and closed position. The means include a lock pin or security pin-bolt 44 which is spring-biased into one of four spaced pin-receiving apertures 45 on the left side of the end member 23. The pin 44 is slidably mounted in an aperture 46 in the spacer block 29 and the outer end of the pin is pivotally connected by a pin 47 to a lock rocker arm 48. The arm 48 is pivotally mounted by a pin 49 on one side of the block 29. A solenoid 50 is mounted near the rocker arm 48 and is provided with a solenoid rod 51 which extends and is connected to the rocker arm at 52. The solenoid 50 also includes a plunger 53 which extends from the side of the solenoid opposite the rod 51. A coil spring 54 holds the rocker arm 48 and pin 44 in the locked position shown in FIG. 3. The solenoid 50 is actuated at the same time as the motor 37 by a manual switch inside and outside of the vault.

In the event of power failure, manual means generally indicated at 55 are provided for opening or closing the ventilator valve which means include a pair of bevel gears 56 and 57. The gear 56 is fixedly mounted on the trunnion 25. However, the gear 57 is mounted on a shaft 58 which is journally mounted in a sleeve 59 on the inside surface of the access cover 34. The shaft extends through an aperture 60 in the cover and an outer end portion 61 is adapted to receive a hand crank (not shown).

The gear 57 is maintained in a position spaced from the gear 56 by a coil spring 62 on the shaft 58. When a crank is attached to the end portion 61, the gear 57 is pressed inwardly against the spring 62. As the gears 56 and 57 are engaged, the inward pressure of the shaft 58 pushes the plunger 53 into the solenoid and thereby disengages the pin 44 from the pin-receiving aperture 45, and the valve is free to actuate upon turning of the crank.

Manual controls for opening and closing the ventilator include an inside switch 63 for opening and closing the valve (FIGS. 1 and 6), an outside switch 64 for closing the valve, and inside and outside indicator lamps 65 and 66. The inside switch 63 is used for opening and closing

the ventilator. The outside switch is used only to close the ventilator. The lamps 65 and 66 are on only when the ventilator is closed. The manner in which the switches and lamps are wired for operating the motor 37 and the solenoid 50 is shown in the schematic wiring diagram of FIG. 6.

The wiring diagram shows the condition of the various switches when the motor is at rest and the valve body 17 is in open position as shown in FIGS. 2, 3, 4, and 5. In arriving at the open position, normally closed LS1 switch 41 was opened by pin 42 (FIG. 5) to stop motor 37 at the end of the previous operation and is held open by pin 42 while valve body 17 is open as shown in FIGS. 3, 4, and 5. The pole LS2 of switch 40 is normally closed as shown while the other pole LS3 of switch 40 is normally open. Aux.CR and Aux.OR are normally closed while 1OR, 2OR, 1CR, and 2CR are normally open. 1OR, 2OR, and Aux.OR are poles of open relay OR, while 1CR, 2CR, and Aux.CR are poles of close relay CR.

When it is desired to close valve body 17 by operation of the close button of inside switch 63 or the outside close button 64, one of these buttons being depressed closes a circuit from line wire 70 to line wire 71 through LS2, Aux.OR, and close relay CR. This energizes CR which, when energized, opens Aux.CR and closes 1CR and 2CR. 1CR, when closed, maintains the circuit for energizing CR. Opening of Aux.CR prevents open relay OR from being energized accidentally while CR is energized. Closing of 2CR starts motor 37.

When motor 37 starts valve body 17 is rotated and as pin 42 (FIG. 5) moves away from LS1 (switch 41), LS1 closes. Valve body 17 continues to rotate until a pin 42 actuates switch 40 when valve body 17 is fully closed. This opens LS2 and at the same time closes LS3. LS3 when closed, lights indicator lamps 65 and 66 inside and outside the vault.

When LS2 opens, CR is deenergized and Aux.CR closes while 1CR and 2CR open stopping motor 37 with valve body 17 closed. Meanwhile, when motor 37 was started by closing 2CR, solenoid 50 also was energized to retract pin 44 permitting rotation of valve body 17 by motor 37. When 2CR opens solenoid 50 also is deenergized permitting pin 44 to lock valve body 17 in the closed position.

With the valve closed, LS1 is normally closed but LS2 (switch 40) is held open by pin 42. Now when it is desired to open valve body 17, the open button of inside control switch 63 is depressed completing a circuit through LS1, Aux.CR and open relay OR. When OR is energized, its contacts 1OR and 2OR close and Aux.OR opens. 1OR maintains the circuit for energizing OR, Aux.OR prevents CR from being energized accidentally while OR is energized; and 2OR when closed starts motor 37 to rotate valve body 17 another 90° arc increment from closed to open position. Upon moving from closed position, pin 42 releases LS2 (switch 41) permitting it to close while LS3 opens extinguishing the signals 65 and 66. Upon arriving at open position, pin 42 actuates LS1, that is switch 41, to open it deenergizing open relay OR and permitting Aux.OR to close and 1OR and 2OR to open stopping motor 37 with valve body 17 open.

The device of the present invention provides an air conditioning construction for a bank vault or similar room requiring a regular periodic change of air. It is used primarily when the vault door is open and is used secondarily for ventilating a vault when a person is inadvertently locked in. The device provides for air conditioning the vault in conjunction with the central air conditioning system of the building in which the vault is located. Security of the vault is not substantially affected. Moreover, the construction includes control means including indicator lights for indicating whether the valve is in the open or closed position.

In the foregoing description, certain terms have been used for brevity, clearness and understanding but no un-

necessary limitations are to be implied therefrom, because such words are used for descriptive purposes herein and are intended to be broadly construed.

Moreover, the embodiment of the improved construction illustrated and described herein is by way of example and the scope of the present invention is not limited to the exact details of construction shown.

Having now described the invention, the construction, operation and use of the preferred embodiment thereof, and the advantageous new and useful results obtained thereby, the new and useful construction and reasonable mechanical equivalents thereof obvious to those skilled in the art set forth in the appended claims.

What is claimed is:

1. Power operated security valve construction for use in air conduit means which extends through one of the walls forming a vault compartment and which communicates between the vault compartment and a source of air under differential pressure with respect to that in the vault compartment; the construction including valve housing means mounted in a vault wall adjacent a vault compartment surface and forming a passage portion of air conduit means extending through such vault wall; a valve body rotatably mounted in said housing having cylindrical wall portions and means forming a radial slot extending through the valve body wall; the valve body being rotatable in the housing in one direction through successive 90° arc increments, valve body rotation through said successive arc increments locating the valve body alternately in open and closed positions; the valve body when in open position establishing air conduit means communication through said radial slot between said vault compartment and a source of air under differential pressure, and the valve body cylindrical wall portions when in closed position cutting off said communication; power means mounted in said housing means in driving engagement with said valve body for rotating the valve body in one direction; drive control means mounted in said housing means including means actuated upon rotation of the valve body to stop rotation after movement through each 90° arc increment; security pin-bolt means operative independently of the drive means automatically to engage and lock the valve body when stopped at least at said closed position after movement through a 90° arc increment; operation control means accessible exteriorly and interiorly of said vault compartment operative to energize the power means when said valve body is in open position to move the valve body from open to closed position; said operation control means including means accessible solely interiorly of said vault compartment operative to energize the power means when said valve body in said closed position to move the valve body from closed to open position; and said operation control means including means actuated to disengage locking engagement between the security pin-bolt means and valve body when the power means is energized to move the valve body from a locked position.
2. The construction defined in claim 1 in which the security pin-bolt means includes a series of recesses formed in the valve body spaced 90° apart around the axis of the rotatable valve body, and a slidably pin-bolt alignable selectively with said recesses and mounted in the housing means normally biased to a position to engage one of said recesses and to lock the valve body when the pin-bolt is aligned with any recess; and in which the means actuated to disengage locking engagement between the security pin-bolt means and valve body includes solenoid means operatively connected with the pin-bolt and energized when the power means is energized.
3. The construction defined in claim 1 in which the power means for driving the valve body includes a drive shaft connected with the valve body; in which manual drive means is mounted on the housing means assessible interiorly of said vault compartment selectively to drivingly engage said drive shaft; and in which said manual means also actuates the security pin-bolt means to disengage

locking engagement between the security pin-bolt means and valve body when the manual means is drivingly engaged with said drive shaft.

4. The construction defined in claim 3 in which the means actuated to disengage locking engagement between the security pin-bolt means and valve body includes a solenoid and a movable solenoid rod actuated by the solenoid when the latter is energized; in which the rod is operatively connected with the pin-bolt means to disengage locking engagement when the solenoid is energized; and in which the manual means engages and actuates the solenoid rod to pin-bolt disengaging position

5

when the manual means is engaged with the valve body drive shaft.
